UNITED STATES PATENT OFFICE.

LEON T. BUCKLER, OF PHILADELPHIA, PENNSYLVANIA, ASSIGNOR TO GEORGE B. CLAY,
OF ELKINS PARK, PENNSYLVANIA.

DRAIN-VALVE DEVICE FOR HYDRANTS.

Application filed November 23, 1920. Serial No. 426,100.

To all whom it may concern:

Be it known that I, LEON T. BUCKLER, a citizen of the United States, residing at Philadelphia, in the county of Philadelphia and State of Pennsylvania, have invented 5 certain new and useful Improvements in Drain-Valve Devices for Hydrants, of which the following is a specification.

One object of my present invention is to 10 provide an improved drain valve device which will be particularly serviceable for use in connection with hydrants such as fire hydrants so as to automatically operate to drain the hydrant after use and thereby 15 prevent freezing of the water as often occurred prior to my invention.

Another object is to make my invention of a simple and durable construction which can be 20 easily manufactured and which can be readily installed.

These objects, and other advantageous ends which will be described hereinafter, I attain in the following manner, reference being had to the accompanying drawings in 25 which—

Figure 1 is an elevation, partly in section, showing a fire hydrant having the device of my invention attached thereto,

Figure 2 is an enlarged plan view of the 30 device of my invention, and

Figure 3 is a transverse section taken on the line 3—3 of Figure 2.

Referring to the drawings, 4 represents a fire hydrant having a depending conduit 5 which is adapted to be positioned in the ground so as to supply water upwardly through the hydrant. My invention includes a body portion 6 which has an externally screw threaded nipple 7 and a depending tubular extension 8; said tubular extension being screw threaded at 9 to permit a drain pipe 10 to be attached thereto as shown in Figure 1; said drain pipe leading to any sewer connection (not illustrated). The body portion 6 has a passage 11 extending therethrough and through the tubular extension 8; said passage leading to the outer end surface 12 of the nipple 7 and being provided with a frusto-conical valve seat 13. The nipple 7 is adapted to be screwed into a hole 14 in the hydrant conduit 5 as clearly shown in Figure 1. The nipple 7 has a forwardly projecting lug 15 to which is pivoted at 16, an arm 17 having

a plate or paddle 18 thereon, the plane of 55 which extends transversely to the direction of movement of the water through the hydrant conduit 5.

A frusto-conical valve 19 has a projection 20 which is pivoted at 21 to the arm 17 60 at a position to the rear of the plate 18. The lower end of the arm 17 has a finger projection 22 adapted to engage the front surface 23 of the lug 15 so that if the arm 17 attempts to fall downwardly upon the pivot 65 16, the finger 22 will engage the surface 23 of the lug and thereby limit the downward pivotal movement of said arm 17. The valve 19 has a part 24 which always remains within the passage 11 so that during an upward 70 movement of the arms 17 from the full line position shown in Figure 3 to the dot-and-dash line position shown in said figure, the valve 19 will always find its way to the seat 13 and thereby close the passage 11 with 75 respect to the interior of the conduit 5.

During the use of the hydrant, the water passing upwardly through the conduit 5 will move the valve 19 into engagement with the seat 13 due to the pressure of the water 80 against the plate 18 and the passage 11 thus being closed will prevent any water from being wasted through the drain pipe 10. After the water has been turned off from the main inlet valve which is positioned 85 below the level of the device, as is customary in the installation of fire hydrants, the water within the conduit 5 above the level of the device will run out through the drain passage 11 and pipe 10 due to the fact that 90 when the pressure of the water is cut off, the plate 18 will fall and the arm 17 will swing on its pivot 16 and thereby withdraw the valve 19 from its seat. The valve 19 being open, the water above the device will 95 therefore drain out of the uppermost portion of the hydrant and in this manner the hydrant is prevented from freezing.

While I have described my invention as taking a particular form, it will be understood that the various parts of my invention may be changed without departing from the spirit thereof, and hence I do not limit myself to the precise construction set forth, but consider that I am at liberty to make 100 such changes and alterations as fairly come within the scope of the appended claims.

Having thus described my invention, what

I claim as new and desire to secure by Letters Patent is:—

1. A drain device for hydrants including a body portion having a drain passage communicating with the interior of the hydrant water conduit; a valve for closing said passage in the direction of escape of the water out of the conduit; and means connected to said valve and movable by water pressure 5 passing upwardly through said conduit to actuate said valve and close said passage; substantially as described.
2. A drain device for hydrants including a body portion having a drain passage communicating with the interior of the hydrant water conduit; a valve for closing said passage; and means connected to said valve and movable by water pressure passing through said conduit to actuate said valve and close 10 said passage, said means including a plate of comparatively wide area pivoted to the valve and having a finger projection adapted to engage the body portion and limit the opening of the valve; substantially as described.
3. A drain device for hydrants including a body portion having a drain passage com-

municating with the interior of the hydrant water conduit; an outwardly closing valve for closing the drain passage, and means 30 connected with the valve and movable, by water pressure in the conduit, to actuate the valve and close the drain passage, said means including an arm pivoted to the body portion and to the valve, substantially as 35 described.

4. A drain device for hydrants including a body portion having a drain passage communicating with the interior of the hydrant water conduit; an outwardly closing valve 40 for closing the drain passage; an arm pivoted to the body portion and the valve; a lug on the body portion; a finger on the arm adapted to limit the downward movement of the arm, and a plate, carried by the arm, 45 adapted to be actuated by water pressure to close the valve.

In testimony whereof I have signed my name to this specification in the presence of two subscribing witnesses.

LEON T. BUCKLER.
